UNITED STATES PATENT OFFICE.

JOHN NEWBERRY REYNOLDS, OF GREENWICH, CONNECTICUT, AND JOHN F. HEARN,
OF PASSAIC, NEW JERSEY, ASSIGNEES TO WESTERN ELECTRIC COMPANY INCOR-
PORATED, OF NEW YORK, N. Y., A CORPORATION OF NEW YORK.

TELEPHONE SWITCHING APPARATUS.

1,314,214.

Specification of Letters Patent. Patented Aug. 26, 1919.

Application filed January 8, 1918. Serial No. 210,862.

To all whom it may concern:

Be it known that we, JOHN NEWBERRY REYNOLDS and JOHN F. HEARN, citizens of the United States, residing at Greenwich, 5 in the county of Fairfield, State of Connecticut, and at Passaic, in the county of Passaic, State of New Jersey, respectively, have invented certain new and useful Improvements in Telephone Switching Apparatus, of which the following is a full, 10 clear, concise, and exact description.

This invention relates to automatic switching mechanism for telephone exchange systems, and pertains more particularly to the provision of a switch for this purpose consisting of an organization of parts, compactly arranged, and coöperating in such manner that a comparatively large 15 number of lines or connecting circuits may be efficiently served with the speed and accuracy necessary in the operation of systems of this character.

The switch construction wherein the principles of the present invention are embodied 20 resembles the type of selective switch described and claimed in an application of J. N. Reynolds, Serial No. 158,190, filed March 29, 1917, inasmuch as there is disclosed in said application a switch having 25 its contacts arranged in multiple layers in superimposed relation to each other. In that application a set of movable contacts or brushes is mounted upon a shaft in coöperative relation to the multiple layers, and 30 by means of switch-operating devices is adapted to be elevated, together with the shaft, into a position opposite any one of said multiple contact layers. Thereupon the necessary electrical and mechanical 35 changes are effected, and by a further operation of the switch-operating devices, the brush set is moved, independently of and at right angles to the brush shaft, to successively engage the contacts of the selected 40 layer.

More particularly, however, the present invention is in the nature of an improvement of the specific type of switch shown in an application to J. N. Reynolds, Serial 45 No. 199,862, filed November 2, 1917. The switch disclosed in this last mentioned application is specially designed to serve a comparatively large number of lines, as for example, 500 or 1000. To this end the mul-

5 tiple contact layers or strips are divided into a plurality of sections, each section being conveniently arranged to include the multiple contacts of 100 lines or trunks. A set of movable contacts is provided for each section and is mounted for sliding movement upon brush carriages. These carriages are securely fastened to a hollow shaft, within which there is a brush controlling shaft adapted for both rotary and longitudinal movements relative to said hollow shaft. A 60 rotary stepping magnet is provided for the purpose of rotating the brush controlling shaft relative to the hollow shaft when the first series of impulses is directed to the switch. This operation results in the pre-determination of the particular set of 65 brushes to be employed in extending the connection. The second series of impulses functions to operate a vertical stepping magnet to elevate both the hollow shaft and the brush controlling shaft into such position that the selected set of brushes are brought into proper relation with the desired layer of contacts. Finally, the last 70 set of impulses operates the vertical stepping magnet to elevate the controlling shaft independently of the hollow brush shaft. This results in causing the selected set of 75 brushes to be thrust in a horizontal movement over the multiple contacts of the level. 80

In accordance with the primary object of the present invention, a selective switch of the above described character, having a capacity for 500 or more lines, is so arranged and organized that but one stepping 85 magnet is required to impart the necessary movements to the movable contacts.

A feature of the invention consists in the provision of a side-switch magnet, which, besides its usual functions of preparing the 90 operating circuits of the switch in the proper sequence, also operates to bring about a number of changes in the mechanical relation of several of the switch parts. By this expedient, certain changes are caused 95 in the coöperation of the actuating members, which control the movement of the brushes, such that the stepping magnet, having performed one operation in response to a series of impulses, may respond to succeeding 100 series of impulses to perform other operations upon the brush controlling mechanism. This novel manner of controlling the me- 105

chanical change-over functions of the switch enables the stepping magnet to accomplish three separate selections.

Another feature resides in the arrangement of means whereby a brush controlling member is moved longitudinally under three distinct and separate conditions, each of these movements being effective in a different selective operation of the switch.

10 Still another feature is the provision of means whereby the movable contacts of the switch are advanced by steps of one character during two selective operations, and thereupon caused to move in the third selective operation by steps of a different character.

15 Other and further objects will become more thoroughly understood from the following description, reference being had to the accompanying drawings, in which Figure 1 is an elevation of a portion of the switch showing the operating devices; Fig. 2 is an elevation of the upper part of the brush shaft, illustrating the method of mounting the 20 brushes in relation to the sections of multiple terminal strips; Fig. 3 is an enlarged detail of a section taken longitudinally of the brush shaft showing the arrangement of the brush selecting device; and Fig. 4 is an 25 enlarged view in perspective of the mechanism for bringing about the mechanical change-over operations during the actuation of the switch.

30 The particular switch chosen to illustrate the principles of this invention is designed for a capacity of 500 connecting circuits, arranged in sections of 100 as shown in Fig. 2. Upon being taken for use in extending a telephone connection, the brush-operating 35 mechanism of this switch actuates in response to the first set of impulses to choose the particular set of brushes allotted to the desired section. In response to the second series of impulses all brush sets are moved 40 vertically until the chosen set is operatively positioned with respect to the desired group or strip of terminals in the section, and finally the set of brushes thus positioned is 45 caused to move transversely to connect with the required set of terminals in the strip. Referring to the drawings, 1 designates the 50 main frame and supporting plate of the switch, which carries the two guiding brackets 2 and 3. A hollow brush shaft 4 is 55 loosely mounted in these brackets so as to be freely movable in a longitudinal direction. Securely fastened to the shaft 4 by means of screws 6, 6, are a plurality of brush carriage supports 5, 5. To assist in retaining 60 said carriage supports rigidly in position the upper portion 7 thereof is fashioned into the form of a sleeve to surround shaft 4. Each support 5 is provided with guide rods 8 upon which is slidably mounted a 65 brush carriage 9. The carriage 9 carries

a set of brushes 10, secured thereto as by means of the insulating blocks 11. A retractile spring 12, one end of which is fastened to the carriage 9 and the other end to the support 5, acts to normally retain 70 the brush carriage in the position shown in the figure.

75 The terminal bank, which, as hereinbefore stated, may be of the type disclosed in the above mentioned application, Serial No. 158,190, consists of flat strips or layers 12, each comprising a plurality of multiple terminals. These terminal strips may be of any desired length to permit access to the multiples thereof by other switches similar 80 to the one shown. In a 500-line switch the strips 12 are arranged in five sections as illustrated in Fig. 2, each section preferably containing ten multiple strips. There are also five sets of brushes 10, one allotted to 85 each section of terminal strips, and so arranged on the shaft 4 that, when said shaft is in its normal position, the brush sets 10 are spaced below the lowermost strip 12 of their individual sections by distances which 90 progressively increase from one section to the next. The object of the arrangement of brushes just described will appear more fully hereinafter. Disposed within the hollow shaft 4 and arranged to extend throughout the entire length thereof, is a brush controlling shaft 13. Shaft 13 is loosely mounted so as to be capable of both rotary and axial movements relative to shaft 4. The upper portion of shaft 13 is provided with 100 a series of reduced cross sections as clearly illustrated in the detailed showing of Fig. 3. There is one of these reduced cross sections for each set of brushes, and with both the shafts 4 and 13 in their normal restored positions, such cross section occurs just below the brush carriage 5. The shaft 13 is also provided with a series of slots 14, one at each of the reduced sections. These slots are cut through the shaft 13 at different 105 angles and are adapted to be brought into registration with slots 15 in the shaft 4 when said shaft 13 is rotated. The angles of the planes of slots 14 are so arranged 110 that successive and equal increments of rotation of shaft 13 bring said slots 14 successively into registration with their corresponding slots 15 of shaft 4. Mounted in each slot 14, by means of a pivot 16 is a latch lever 17, the lower end of which is 115 provided with a hook 18, and the upper end with the cam surface 19. With the shafts 13 and 4 in their normal relative position, the lever 17 is retained within the slot 14 as shown in Fig. 3. A more detailed disclosure of the arrangement and purpose of the slots in the brush controlling shaft is given 120 in the above-referred-to application, Serial No. 199,862. And since the present invention is not directed to this particular ar- 125

130

arrangement of the brush controlling shaft, it is believed unnecessary to give a more detailed description thereof.

Secured to the main plate 1, is a supporting structure comprising the plates 20 and 21, which are fastened to each other by screw 22. Plates 20 and 21 are respectively provided with brackets 23, 24 and 25, 26, each having a circular hole in the end thereof, arranged in vertical alignment. A ratchet wheel 27 has a hollow bearing hub 28 which is journaled for rotation in the brackets 23 and 25. The hub 28 may be enlarged as shown at 29 to prevent axial displacement of ratchet 27, or as an alternative, a split sleeve may be sprung over the hub to serve as a spacing member between said ratchet and the bracket 23. On the other side of bracket 23, a cup-shaped member 30 fits on over the end of bearing hub 28, and is secured thereto by a set screw 31. The upper or closed end of this cup contains a rectangular aperture 32, best seen in Fig. 4. Adjacent to, and in axial alignment with hub 28, is a second hollow bearing hub 33, said latter hub being journaled for rotation in the brackets 24 and 26. A ratchet wheel 34 is securely fastened to bearing hub 33 and is retained against longitudinal displacement by the spacing sleeve 35. On the lower end of hub 33, a cup 36, similar to cup 30, is fitted and secured by a set screw 37. Cup 36 is likewise provided with a rectangular aperture 38. A coiled spring 39 is wrapped about the hub 33 with one end fastened to said hub and the other end secured to the bracket 25. Normally this spring is in a substantially untensioned condition, but after being wound up by a clockwise rotation of hub 33 it exerts its force to return said hub to normal as soon as the same is released. Mounted upon pivots 40 is a pair of holding dogs 41 and 42 which co-operates respectively with ratchet wheels 34 and 27 to hold the same in their adjusted positions against the tension of spring 39. Said dogs 41 and 42 are provided respectively with springs 43 and 44, both fastened to a lug 45 on plate 20, and the tension of which tends to hold said dogs in engagement with their respective ratchet wheels. These dogs are also equipped with anti-friction rollers 46 and 47 adapted to be engaged by actuating devices, as will clearly appear hereinafter, to retract the dogs from their holding engagement with ratchets 34 and 27. The holding dogs 41 and 42 are so arranged that dog 42 may be released without affecting dog 41, but dog 41, when retracted, acts to release both dogs from their engagement with ratchets 34 and 27.

A rectangular strip or bar 48 is arranged within the hollow bearing hubs 28 and 33 and passes loosely through the apertures 32 and 38 in the cups 30 and 36 respectively.

The upper end of this bar passes into a slot in the end of the brush controlling shaft 13, and is secured thereto as by means of rivets 49. The intermediate portion of the bar 48 is given a uniform twist so that its flat sides 70 form substantially helical surfaces. This helical twist is clearly shown at 50 in Fig. 4, and is so arranged in the hollow hub 33 below the slot 32 in cup 30, when all parts are in normal position, that upon an upward movement of shaft 13, the said twisted section of bar 48 will engage the slot 32 in cup 30 to rotate the shaft 13. It will now be seen that the pitch of this helical portion of bar 48 may be so adjusted 75 that by taking one upward step the shaft 13 is rotated a sufficient distance to bring a slot 14 into registration with a slot 15 in shaft 4 corresponding to that set of brushes 80 which is allotted to the first section of terminals 12. In a like manner two steps place the slots 14 and 15, corresponding to the second set, in registration. It will also be seen that by providing the bar 48 with the proper number of turns any desired number 85 of brush sets may be successively selected 90 as the twisted portion of said bar passes through the rectangular slot 32.

At the lower end of hollow shaft 4 is secured a collar 51 which carries the spring-held pawl 52. This pawl has a cam surface which is adapted to engage momentarily the anti-friction roller 46 of dog 41 as the shaft 4 drops to its normal position. During the upward motion of shaft 4, the pawl spring 95 100 105 110 115 120 125 130 135 140 145 150 155 160 165 170 175 180 185 190 195 200 205 210 215 220 225 230 235 240 245 250 255 260 265 270 275 and release of the switch is effected at the proper periods in the operation of the switch mechanism. The manner of controlling the locking mechanism between the 5 brush shaft and toothed stepping bar, the change-over from long to short steps of the stepping pawl, and the functions and operation of the cams driven by the side-switch magnet are all fully shown and described in 10 the said application to J. N. Reynolds, Serial No. 199,862, and will not, therefore, be further discussed at this time.

Considering the operation of the improved switching apparatus, it will be assumed 15 that a connection is desired with a circuit appearing in the second hundred, or in other words, one which is represented by multiple terminals in the second section of contact layers from the bottom in Fig. 2. 20 The first series of impulses will, accordingly, be instrumental in predetermining the second set of brushes 10 as the set to be subsequently employed in selecting and making connection with the desired set of contacts.

25 This first series, which comprises two impulses, operates the stepping magnet 59 correspondingly, and by means of the armature actuated pawl 57 the toothed bar 56 is given two vertical steps. The stroke of armature 30 58 is so adjusted that for each step the bar 56 is moved a distance equal to two teeth of said bar. Due to the locking member 60 being in engagement with a notch in bar 56, and due to the screw 61 being in engagement 35 with a groove in shaft 13 as above explained, the bar 56 in its upward movement at this time carries with it both the brush shaft 4 and the controlling shaft 13. The upper straight surface of the restoring 40 pawl 52 engages the roller 46, which rotates said pawl against the tension of spring 53 and permits it to escape without disturbing the holding dog 41. At the same time upon the first vertical movement of the bar 48 the 45 twisted portion thereof encounters the slot 32 in cup 30. Referring to Fig. 4, it will be seen that this engagement tends to rotate said cup in a counter-clockwise direction. But the cup 30 being secured to ratchet 27,

50 which is restrained from such rotation by the dog 42, the result is that the bar 48 and shaft 13 are forced to rotate in the opposite direction. Such rotation of the bar 48, due to its engagement with the slot 38 in the 55 lower cup member 36, causes said cup, together with the ratchet 34, to rotate in a like manner. This results in the coiled spring 39 being wound up, where it is held by the dog 41, which engages the next tooth 60 of ratchet 34 as soon as the toothed bar 56 moves the shaft 13 one complete vertical step. The transmission of the second and last impulse of the brush selecting series in a like manner moves the shaft 13 up a 65 second vertical step, which in turn advances

the helical twist 50 a corresponding distance through the slot 32 to thereby impart a second rotary step to shaft 13, which, as before, continues the tensioning of spring 39 and the advancement of ratchet wheel 70 34 another step. At the end of these two vertical steps of the brush shaft 4 and controlling shaft 13, and also the two rotary steps of shaft 13 which simultaneously accompany them, said shaft 13, as before explained, is rotated through an angle sufficient to bring the slot 14 corresponding to the second set of brushes into registration with the slot 15 in the shaft 4. Moreover, the shaft 4 by its elevation of two long steps 80 has placed the second set of brushes 10 in such position that one more long step is required to move said brush set into operative relation to the first multiple terminal strip 12 of the second section. A holding pawl 76 85 is arranged to maintain the operated parts in their elevated position.

At the time of the transmission of the first set of impulses to the switch, the side-switch magnet 63 was energized in any well-known manner. Upon deenergizing at the end of this set, the side-switch cams 67 and 68 are advanced one rotary step, moving the side switch into second position. The periphery of cam 67 is so arranged as not to affect roller 74 at this time. However, one of the pins 72 on said cam is moved sufficiently to engage and rotate the pivoted arm 73. The end of arm 73 bearing on roller 47 moves and holds the dog 42 out of engagement with ratchet 27. The second impulse set, corresponding to the desired multiple layer 12 in the second section, is now directed to the switch. The stepping magnet 59 actuates as before to move the 100 toothed bar 56 vertically in steps equal to two teeth of said bar for each impulse received. Also the side-switch magnet 63 is energized preparatory to advancing the side switch to third position. The upward movement of bar 56 in response to the second impulse series acts, as in the case of the first series, to simultaneously elevate the brush shaft 4, controlling shaft 13, and the bar 48. The remaining portion of the twist 50 105 in the bar 48 now passes through the slot 32 in cup member 30, and consequently forces a relative rotation between the cup 30 and the bar 48. But the dog 42 being held away from ratchet 27, said ratchet and cup are free to rotate in the bearings 23 and 25, being retarded merely by their own inertia. This, however, is so slight as compared with the inertia of the bar 48 and shaft 13 that the helical portion 50, in passing up through cup 30, rotates said cup and the ratchet 27 in a counter-clockwise direction, while the motion of shaft 13 is purely a longitudinal one. Thus the slot 14 in shaft 13 and slot 15 in shaft 4, previously 110 115 120 125 130

registered, are maintained so during the second selective operation of the switch apparatus. The selected brush set 10 is now resting in operative relation to the multiple layer 12, of the second hundreds group, corresponding to the number of impulses sent to magnet 59 in the second series. Side-switch magnet 63 again de-energizes and passes the side switch to position 3. Rotation of the cam disk 67 now brings one of its peripheral surfaces into engagement with roller 74, which rotates member 75 to unlock the toothed bar 56 from shaft 4 and in turn locks said shaft 4 to the switch frame. This movement of member 75 also prepares for a change-over in the operation of the stepping magnet armature from long to short steps. As referred to, these features are all well explained in the above mentioned application, Serial No. 199,862. The pin 72 of the cam 67, which operated the lever 73 when the side switch took its first step, still retains said lever actuated after the side switch has advanced a second step. The curved end 76 of lever 73 permits of this action, and the reason therefor will be taken up later in the description.

Upon the third and final series of impulses being sent to the switch, magnet 59 vibrates its armature 58, and the pawl 57, in response thereto, steps the bar 56 up a distance equal to two teeth for the first impulse of such series. The shaft 4 which is now unlocked from toothed bar 56 and locked to the switch frame holds the selected set of brushes 10 accurately positioned with respect to the selected layer 12 in the section. Therefore, the bar 56 by moving upward under these conditions carries with it only the brush controlling shaft 13. The shaft 13 by moving relatively to shaft 4 causes the cam surface 19 of latch lever 17 to engage screw 6, Fig. 3, with which it is now in vertical alignment, to thereby swing the lever 17 out through the registered slots in shaft 13 and shaft 4. The hook 18 engages the bell-crank lever 77 which in turn imparts a horizontal movement to the brush carriage 9 and its associated brush set. Thus, at the end of the first impulse of the third series the shaft 13 is moved vertically one long step, the brush latching mechanism is operated, and the chosen set of brushes 10 is moved into contact with the first set of multiple terminals in the selected layer 12. Thereupon, as previously referred to, the change-over operation occurs to limit the stroke of armature 58 to steps corresponding to a single tooth of the bar 56, so that the remaining impulses of the series operate to advance the brush set 10 in short steps from one terminal set to the next until the proper set is finally reached. The side switch then moves

forward into position 4. The cam disk 67 does not alter the position of member 75, but pin 72 now escapes the hooked end of lever 73, permitting said lever to restore and the dog 42 to reengage ratchet wheel 27.

When it is desired to restore the switch to normal position, side-switch magnet 63 is energized and automatically steps the side-switch cams 67 and 68 and arm 70 around to position 8. The cam 67 is so fashioned that upon passing to position 8, it engages the roller 74 to rotate member 75 in the opposite direction from that caused when said cam took its second step. This movement of member 75 serves to release the toothed bar 56, which drops with the shaft 13 toward the normal position. Downward motion of shaft 13 causes the brush carriage to be withdrawn, assisted by spring 112, and also returns the latch lever 17 within its recess in shaft 13. When the toothed bar 56 drops sufficiently to bring it into its normal position relative to the shaft 4, the locking member 60 unlocks shaft 4 from the switch frame, and locks it to the bar 56. Thereupon, both shafts 4 and 13 return to their normal restored position. Just before reaching this position, however, the cam surface of pawl 52 engages roller 46 to momentarily withdraw both dogs 41 and 42 from their holding relation with ratchets 34 and 27. The spring 39, which was tensioned during the operation of the switch, immediately restores the hub bearing 33 and ratchet 34 back to normal and in so doing, rotatively restores the twisted bar 48 and shaft 13 to normal. At this time, the magnet 63 is given its final energization, which acts to return the side switch to its first position and places cams 67 and 68 in condition to perform another cycle of operations. All parts of the switch are thus in their normal position.

Considering again the operation of the novel mechanism herein disclosed for transforming a linear stepping motion into a rotary stepping one for selecting purposes, a further description will now be given of the necessity of retaining the holding dog 42 out of engagement with ratchet 27 during the third selective operation of the switch mechanism. To this purpose another specific instance is assumed, in which the summation of impulses comprising all three series of selective impulses is less than six. This occurs, for example, when connection is desired with the first set of multiple terminals in the first layer of the first section of 100 lines, in which case but three impulses are necessary to effect the connection. In this case only $\frac{1}{2}$ of the twisted portion 50 of bar 48 passes through the slot 32 in cap 30 during the first two selective movements of the switch. Consequently, in order that the remaining portion of the twist 50 will not

produce rotation of shaft 13 and thereby throw slots 14 and 15 out of registration during the third selective movement, it is necessary to hold the ratchet 27 unlocked during this period. The manner in which this is accomplished was clearly explained hereinbefore.

While the invention is shown as embodied in a switch of the 500-line type, it is obvious 10 it may readily be adapted to switches of any desired size.

What is claimed is:

1. The combination in a switch, of a contact bank arranged in sections and groups, 15 a brush shaft, an auxiliary shaft, said shafts being arranged to be advanced simultaneously in two separate selective movements to select first a section and then a group of contacts in said section, said auxiliary shaft being arranged for further movement to select a set of contacts in the group, and means for operating said shafts.

2. The combination in a switch, of a contact bank arranged in sections and groups, 25 a brush shaft, an auxiliary shaft, said shafts being arranged to be advanced simultaneously in two separate longitudinal movements to select first a section and then a group of contacts in said section, said auxiliary shaft being arranged for further longitudinal movement independently of said brush shaft to select a set of contacts in the group, and means for operating said shafts.

3. The combination in a switch, of a contact bank arranged in sections and groups, a hollow brush shaft, an auxiliary shaft within said hollow shaft, said shafts being arranged to be advanced simultaneously in 40 two separate selective movements to select first a section and then a group of contacts in said section, said auxiliary shaft being arranged for further movement to select a set of contacts in the group, and means for operating said shafts.

4. The combination in a switch, of a contact bank arranged in sections and groups, a hollow brush shaft, an auxiliary shaft within said hollow shaft, said shafts being arranged to be advanced simultaneously in 50 two separate longitudinal movements to select first a section and then a group of contacts in said section, said auxiliary shaft being arranged for further longitudinal movement independently of said hollow shaft to select a set of contacts in the group, and means for operating said shafts.

5. The combination in a switch, of a contact bank arranged in sections and groups, 60 a brush shaft, an auxiliary shaft, said shafts being arranged to be advanced simultaneously in two separate selective movements to select first a section and then a group of contacts in said section, said auxiliary

shaft being arranged for further movement 65 to select a set of contacts in the group, and a single magnet for operating said shafts.

6. The combination in a switch, of a contact bank arranged in sections and groups, a brush shaft, an auxiliary shaft, said shafts 70 being arranged to be advanced simultaneously by long steps in two separate selective movements to select first a section and then a group of contacts in said section, said auxiliary shaft being arranged to be 75 further advanced by short steps to select a set of contacts in the selected group, and a single stepping magnet for operating said shafts.

7. The combination in a switch, of a contact bank arranged in sections and groups, a brush shaft, an auxiliary shaft, said shafts being arranged to be advanced simultaneously by long steps in two separate movements to select first a section and then a 85 group of contacts in said section, said auxiliary shaft being arranged to be further advanced by short steps to select a set of contacts in the selected group, means for changing the operation of the auxiliary 90 shaft from long to short steps, and a single stepping magnet for actuating said shafts.

8. The combination in a switch, of a contact bank arranged in sections and groups, a hollow brush shaft, an auxiliary shaft 95 within said hollow shaft, said shafts being arranged to be advanced simultaneously by long steps in two separate longitudinal movements to select first a section and then a group of contacts in said section, said auxiliary 100 shaft being arranged to be further advanced longitudinally by short steps and independently of said hollow shaft to select a set of contacts in the selected group, a controlling magnet for changing the operation 105 of said auxiliary shaft from long steps to short steps, and a single stepping magnet for actuating said shafts.

9. In a switch, a contact bank comprising a plurality of sections, each section comprising superimposed unit layers, each layer comprising a group of multiple contacts, a brush shaft, an auxiliary shaft, said shafts being arranged to be advanced simultaneously in two separate vertical movements to 115 select first a section and then a group of contacts in said section, said auxiliary shaft being arranged to again move vertically and independently of said brush shaft to select a set of multiple contacts in the selected 120 group, and a single magnet for operating said shafts.

10. In a switch, a contact bank comprising a plurality of sections, each section comprising superimposed unit layers, each layer 125 comprising a group of multiple contacts, a hollow brush shaft, an auxiliary shaft within said hollow shaft, said shafts being arranged

- to be advanced simultaneously in two separate vertical movements to select first a section and then a group of contacts in said section, said auxiliary shaft being arranged 5 for further vertical movement independently of said hollow shaft to select a multiple contact in the selected group, mechanical means for controlling the operation of said shafts, and a stepping magnet for operating said 10 shafts.
11. In a switch, a contact bank arranged in sections and groups, a brush shaft, an auxiliary shaft, means for moving simultaneously said brush shaft longitudinally and said 15 auxiliary shaft longitudinally and rotatively to select one of said sections, means for simultaneously moving both shafts longitudinally to select a group in the selected section, and means for moving said auxiliary shaft longitudinally to select a contact 20 in the selected groups.
12. In a switch, a contact bank arranged in sections and groups, a hollow brush shaft, an auxiliary shaft within said hollow shaft, 25 means for moving simultaneously said hollow shaft longitudinally and said auxiliary shaft rotatively to select one of said sections, means for simultaneously moving both shafts longitudinally to select a group of contacts 30 in the selected section, and means for moving said auxiliary shaft longitudinally to select a contact in the selected group.
13. In a switch, a contact bank arranged in sections and groups, a brush shaft, an auxiliary shaft, means for longitudinally advancing said shafts together by long steps and for simultaneously advancing said auxiliary shaft rotatively to select one of said sections, means for advancing both shafts 40 longitudinally by long steps to select a group of contacts in the selected section and means for again advancing said auxiliary shaft longitudinally by short steps to select a contact in the selected group.
- 45 14. In a switch, a contact bank arranged in sections and groups, a hollow brush shaft, an auxiliary shaft within said brush shaft, means for advancing said shafts in unison longitudinally by long steps and for simultaneously rotating said auxiliary shaft to select one of said sections, means for advancing both shafts longitudinally by long steps to select a group of contacts in the selected section, and means for advancing said auxiliary shaft longitudinally independently of 55 said brush shaft to select a contact in the selected group.
15. In a switch, a frame, a brush shaft and an auxiliary shaft mounted upon said frame, means for advancing both shafts longitudinally in a first selective movement, mechanism for imparting rotation to the auxiliary shaft during said movement, means for advancing both shafts longitudinally in a second selective movement, mechanism for locking said brush shaft to the switch frame, means for again advancing said auxiliary shaft in a third selective movement, and a magnet for controlling both of said mechanisms. 70
16. In a switch, a frame, a hollow brush shaft mounted upon said frame, an auxiliary shaft within said brush shaft, means for advancing both shafts vertically in a first selective movement, mechanism for imparting rotation to the auxiliary shaft during said movement, means for advancing both shafts vertically in a second selective movement, mechanism for thereupon locking said brush shaft to the switch frame, means for again advancing said auxiliary shaft vertically and independently of said brush shaft, and a magnet for controlling both of said mechanisms. 75
17. In a switch, a brush shaft, an auxiliary shaft, means for advancing both shafts longitudinally by steps of one character in a first selective movement, mechanism for imparting rotation to the auxiliary shaft simultaneously with its longitudinal 90 movement, means for again advancing both shafts longitudinally by steps of the same character in a second selective movement, mechanism for thereupon locking said brush shaft against further movement, means for again advancing said auxiliary shaft longitudinally by steps of a different character in a third selective movement, mechanism for changing the operation of the auxiliary shaft from steps of one character to steps 95 of the other character, and a single magnet for actuating each of said mechanisms. 100
18. In a switch, a hollow brush shaft, an auxiliary shaft within said brush shaft, said shafts being normally locked against relative longitudinal movement, means for advancing both shafts longitudinally by long steps in a first selective movement, mechanism for imparting rotation to the auxiliary shaft simultaneously with its longitudinal 105 movement, means for again advancing both shafts longitudinally by long steps in a second selective movement, mechanism for thereupon unlocking said shafts and for locking said brush shaft against further 110 movement, means for again advancing said auxiliary shaft by short steps in a third selective movement, mechanism for changing the operation of the auxiliary shaft from long to short steps, and a magnet for actuating all of said mechanisms. 115
19. In a switch, a contact bank arranged in sections and groups, a hollow brush shaft, an auxiliary shaft mounted within said brush shaft for rotary and longitudinal 125 movements relative thereto, a helically shaped member secured to said auxiliary shaft, a locking device for normally locking

8
said shafts against relative longitudinal movement, means for moving said shafts longitudinally, mechanism coöperating with said helical member to impart rotation to said auxiliary shaft simultaneous with said longitudinal movement to select one of said sections, means for again moving said shafts longitudinally to select a group of contacts in the selected section, mechanism for thereupon actuating said locking device to unlock said shafts from each other and to lock the brush shaft against further movement, means for again moving said auxiliary shaft longitudinally to select a contact in the selected group, and a magnet for controlling both of said mechanisms.

20. In a switch, a contact bank arranged in sections, each section comprising a plurality of layers, each layer comprising a group of multiple contacts, a brush shaft, a plurality of brushes mounted thereon, one for each of said sections, an auxiliary shaft, means for moving both shafts vertically and for simultaneously rotating the auxiliary shaft to select one of said brushes and to position the selected brush in operative relation to its individual section, means for again moving both shafts vertically to position said brush in operative relation to a desired group of contacts in the section, and means for again moving the auxiliary shaft vertically to move said brush over the contacts of the selected group.

21. In a switch, a frame, a brush shaft and an auxiliary shaft mounted upon said

frame, means for advancing both shafts longitudinally in a first selective movement, mechanisms for imparting rotation to the auxiliary shaft during said movement, means for again advancing both shafts longitudinally in a second selective movement, mechanism for thereupon locking said brush shaft to the switch frame, means for again advancing the auxiliary shaft longitudinally in a third selective movement, mechanism for releasing said shafts, and a single electro-mechanical device for controlling all of said mechanisms.

22. In a switch, a brush shaft, an auxiliary shaft, means for advancing both shafts longitudinally by long steps in a first selective movement, mechanism for simultaneously imparting rotation to the auxiliary shaft, means for again advancing both shafts longitudinally by long steps in a second selective movement, mechanism for thereupon locking said brush shaft against further movement, means for again advancing the auxiliary shaft longitudinally by short steps in a third selective movement, mechanism for changing the operation of the auxiliary shaft from long steps to short steps, mechanism for releasing said shafts, and a single magnet for controlling all of said mechanisms.

In witness whereof, we hereunto subscribe our names this 31st day of December A. D., 1917.

JOHN NEWBERRY REYNOLDS.
JOHN F. HEARN.
